UNITED STATES PATENT OFFICE.

RALPH M. SHARAF, OF NEW YORK, N. Y., ASSIGNOR TO R. M. SHARAF MACHINE CO.,
OF BOSTON, MASSACHUSETTS, A CORPORATION OF MASSACHUSETTS.

CLOTH FOLDER FOR SEWING MACHINES.

Application filed May 9, 1918. Serial No. 233,471.

To all whom it may concern:

Be it known that I, RALPH M. SHARAF, a citizen of the United States, and resident of the borough and county of the Bronx, city 5 and State of New York, have invented certain new and useful Improvements in Cloth Folders for Sewing Machines, of which the following is a specification.

My present invention relates to mechanism 10 for folding the edge of a piece of cloth in a sewing machine, and is particularly adapted for use when an auxiliary material, such as a strip of lace, is to be sewed to the folded edge of the cloth.

15 In the accompanying drawings, I have illustrated a typical example of my invention, as applicable to a two-needle zig-zag sewing machine provided with cutters which sever a strip from the cloth between the lines 20 of the stitches, the opening or gap thus produced being bridged by the lace or auxiliary material, which is sewed to the cloth folded at the edges of said opening. This general arrangement is disclosed more fully and 25 claimed in other applications for patents filed by me and now pending in the United States Patent Office, for instance, Serial No. 92,141 filed April 19, 1916. My present application relates to an improved construction 30 and arrangement of the cloth folder, which may be used in connection with sewing machines of various types, and I do not wish to restrict myself to the particular species of sewing machine illustrated.

35 In said drawings, Fig. 1 is a side elevation of a presser foot carrying my improved folder, together with the movable knife and other parts referred to hereinafter, said knife being in its lower position. Fig. 2 shows a front view of the presser foot, with parts broken away; Fig. 3 is a vertical section of the presser foot on line 3—3 of Fig. 2, showing the movable knife in its upper position; Fig. 4 is an inside view of one of 40 the side pieces of the presser foot with a folder thereon; Figs. 5, 5^a and 6 are partial front views of the presser foot, with the throat plate and certain other parts in section, showing the folder adjusted to two 45 different positions, Fig. 5^a showing the folder raised; Fig. 7 is a top view of the throat plate with parts in section; Fig. 8 is an enlarged detail top view illustrating the operation of the cutter, of the folder, and 50 of the stitching mechanism; Fig. 9 is a bot-

tom view of the presser foot and one-half of the throat-plate; Fig. 10 is a detail perspective view of the movable knife and its holder; Fig. 11 is a perspective view of the folder; Fig. 12 is a partial bottom view corresponding to Fig. 8; Fig. 13 is a perspective view of the front part of the presser foot; Fig. 14 is a diagram illustrating the relation of the cutting, folding, and stitching operations. Fig. 15, is a detailed plan view of 65 the body of the presser foot, and Fig. 16 is a detailed sectional view taken on the line 16—16 of Fig. 9.

The presser foot illustrated herein comprises a rear part 19 which is rigid or integral with the usual presser foot bar 20, a front part 21, two side members 22, 22' which form a connection between the rear part 19 and the front part 21, to which they are secured by screws 23, or otherwise, and 70 a front cover 24 secured (as by screws 25) on the outside of the front part 21. The front edge of the rear part 19 is spaced from the rear edge of the front part 21, forming, between the side members or plates 22, 22', a transverse slot 26 preferably provided at its ends with vertically extending transversely elongated openings 26' forming a part of the needle holes 19' through which the needles 27 reciprocate up and down, and 80 as this particular foot is intended for a zig-zag sewing machine, it will be understood that the needles have a lateral motion in addition to their reciprocating movement; that is, at one stitch the needle will go down near 90 the inner end of the opening 26' and at the next stitch, near the outer end of this enlargement. The needle holes 19' and openings 26' may be formed partly in the rear part 19 and partly in the side members 22, 22'. Any well-known or approved mechanism 95 may be employed for imparting the desired motion to the needles 27.

The upper surface of the front part 21 is curved to form a support and guide for an 100 auxiliary material, such as lace 28, the edges of which are guided by the side plates 22, 22', and which passes downwardly through the slot 26, in substantially the manner set forth in my above mentioned application. 105 Any suitable means, such as the lace feeder disclosed in said application, may be employed for carrying the lace rearwardly and downwardly over the upper face of the front part 21 and through the slot 26. At 29 I 110

have indicated a vertically reciprocating bar which operates the lace feeder (not shown) to feed the lace at each downward movement of said bar 29.

5 The bar 29 is shown as provided with arms or brackets 30 extending downwardly and forwardly and arranged exteriorly of the side members 22, 22', so as to clear them as the said brackets move up and down with 10 the bar 29. These brackets are provided with horizontal aligning pins 31 extending inwardly or toward each other, and guided in vertical slots 32 extending through the side plates 22, 22', and through the outer 15 faces of the front part 21. The inner ends of these pins 31 fit into grooves 33 provided on the knife carriers 34, the longitudinal direction of said grooves forming an angle with the vertical path of the pins 31. 20 Each knife-carrier has a slotted or forked lower end 34' to receive the upper end of the knife or blade 35 secured thereto rigidly, as by a pin or screw 36.

Each carrier 34 with its blade 35 is fitted 25 within a recess 37 of the front part 21, the slots 32 extending through the outer walls of said recesses. The front cover 24 forms a front wall for the two recesses 37, and also forms an inclined guide for the front edges 30 of the knife-carriers 34, the rear edges of which are guided along the rear walls 37' of the corresponding recesses 37, which rear walls are inclined as shown and parallel to the guide surfaces of the front cover 24. 35 This inclination is lengthwise of the line of feed indicated by the arrows.

The upper knife 35, reciprocating along and below the presser foot in the inclined path described, cooperates with a stationary knife 38 which is secured to the 40 throat plate 39. This knife is located on the inside of the movable knife, and is preferably pressed outwardly, that is to say, toward the path of the movable knife, by a spring 40, tending to swing the knife 38 about the vertical pivot 41 which connects it with the throat plate. When the movable knife is in its upper position, and therefore out of engagement with the stationary knife 38, the latter is held (by the 45 spring 40) in contact with an adjustable stop, say a screw 42 carried by the throat plate, so that the normal position of the knife 38 may be varied as desired.

50 The throat plate 39 (which, as shown, may be made in two separate halves or sections) has transversely-elongated needle-openings or guides 43 corresponding in position to the openings 26' of the presser foot slot 26, that is to say, each guide opening 43 is substantially in vertical alignment with one of the openings 26'. The throat plate also has openings 44 in which the feed dogs (not shown) move lengthwise of the line of feed, 55 being operated by any suitable mechanism.

Between the longitudinal vertical planes in which the movable knives 35 reciprocate, and the longitudinal vertical planes parallel thereto in which the needles move when in their inner positions, I arrange my improved folders 45, which are shown as secured to the presser foot, within recesses 46 on the inner faces of the side plates 22, 22'. The folders are made of elastic material (steel), their upper ends being secured to the respective side plates in a substantially rigid manner, and their lower portions being bent first inwardly and horizontally, at 45', substantially level with the bottom surface of the presser foot, and then vertically downward below said bottom surface, as at 45'', the portions 45', 45'' forming the cloth-engaging or active portion of the folder. The elasticity of the folders 45 tends to throw them apart, or outwardly 80 against adjustable stops, such as screws 47, which govern variably the normal position of the folders.

As will be evident from Figures 1, 3, 7, 8, 9 and 14, the rear ends of the folders 45 are arranged very close to the path of the needles, and slightly forward of said path, with the rear extremities of the outer surfaces of the depending folder ends 45'' in the longitudinal line intersecting the vertical line in which the needles descend when in the inner position (Fig. 8), or these extremities of said surfaces may be located slightly to one side of said line. The knives 35, 38 begin to cut at the point *a* (Figs. 3 and 14) which is forward of the point of action of the folders, and as the movable knives descend, the cut extends forwardly to the point *b*. The front part 21 of the presser foot is recessed as at 21' to receive the lower ends of the folders. Preferably, the recesses 21' extend upwardly a sufficient distance to enable each folder to be lifted to an inactive position (see Fig. 5^a). The upper end of the folder shank may be formed as a handle 48 projecting from the presser foot to enable the folder to be shifted manually to the active or the inactive position. Bends 48', 48'', cooperating with sockets 46', 46'', may be used to hold the folder against accidental movement in either its upper or its lower position.

The operation is as follows:

The cloth or piece of goods 49 is fed intermittently in the direction indicated by the arrows; at the time of this feed movement, the lace feed bar 29 and the movable knives 35 are in their upper position, Fig. 3. The cloth 49 having temporarily come to rest, the bar 29 and knives 35 descend while the cloth 49 is stationary, and the diagonally-moving upper knives 35, in conjunction with the stationary lower knives 38, produce two parallel longitudinal shearing cuts in the cloth, beginning at the points 120 115 125 130

a and progressing forwardly to the points *b*.

At the same time, the lace or other auxiliary material 28 is fed rearwardly over the upper surface of the presser foot section 21 through the slot 26, to be applied on top of the cloth 49. The piece or strip 49' between the two parallel cuts is severed completely from the cloth and drops off as the finished article is taken from the machine. This cloth-cutting and lace-feeding action (with the cloth stationary), is followed immediately by a stitching movement of the needles, and then by another rearward feed of the cloth 49, during which the movable knives 35 remain in the upper position (Fig. 3). This feed movement of the cloth carries the cut or slit portions of the cloth against the folders, which project into said slits, and the inner edges 49" of the main or outer portions of the cloth are given a right-angle or quarter-turn downwardly by engagement with the outer surfaces of the depending folder ends 45" and with the rearwardly-oblique edges of throat plate openings 39', as shown in Figs. 5, 6, 8 and 12. Figs. 7 and 12 show that these oblique edges of the openings 39' are substantially parallel to the outer surfaces of the folder ends 45". The cycle of operations is then repeated.

The intermittent feed of the cloth 49 will carry the downwardly folded edges 49" gradually to the stitching point. In their inner positions the needle 27 will go down slightly on the inside of the right-angle folds at the edges 49", so that the inner rows of stitches will clear said folds and pass only through the lace 28. The next stitch of the needle 27 will occur when this needle is in the outer position (farthest to the left in Figs. 8 and 14), and the outer row of stitches will pass only through the main portion of the cloth 49. As the needle 27 ascends in its outer position, it will draw upwardly the portion of the thread 50 which forms a loop around the folded edge 49" and by tightening said loop will pull said edge upwardly from the throat plate and against the bottom surface of the main portion of the cloth, so that this edge will now be horizontal, or flat against the under surface of the cloth, as shown in Figs. 8 and 12. The outer row of stitches will be clear (that is to say, exteriorly) of the extreme or free edge of the portion 49" in its fully folded position. In the diagram Fig. 14, the line A indicates the longitudinal line of the cut made by one of the pairs of knives 35, 38; the line B, the longitudinal line in which lie the inner positions of the needle 27 and the rear extremity of the outer surface of the active folder portion; the line C (equidistant from A and D) the bend of the finished fold; the line D, the free or cut edge of the finished fold;

and the line E, the longitudinal line in which lie the outer positions of the needle 27. The cut made by the knives at one operative stroke begins at *a* and ends at *b*; the folder begins to engage the cut fabric at *c* and remains in engagement therewith to *d*; and stitching takes place in the transverse plane indicated by the line *e*.

The lateral adjustment of the stationary knives 38 is for the purpose of bringing them into proper co-operative relation to the movable knives 35, particularly as different knives may be used for different kinds of goods. The springs 40 enable the stationary knives to yield slightly in a lateral direction, and keep them in, or return them to, their normal position.

The lateral adjustment of the folders 45 enables their active portions, and particularly their depending ends 45", to be brought closer to or farther away from the knives, it being understood that the spaces between the outer walls of the throat plate openings 39' and the paths of the movable knives 35 are sufficiently wide to permit of such adjustment. The openings 39' are those which receive the active portions of the knives 35, 38 and the depending ends 45" of the folders. When the cloth 49 is relatively thin, as indicated in Fig. 5, the folders are

adjusted outwardly to bring them near to the outer walls of the openings 39', it being understood that the width of the space between said outer wall and the folder end 45" is approximately equal to the thickness of the cloth. Thus, if the cloth is relatively thick, as in Fig. 6, the folders will be adjusted farther inward. The elastic character of the folders 45 enables them to yield inwardly to accommodate any uneven places in the cloth 49. The lateral adjustment of the folder may bring its rear end slightly out of the longitudinal plane indicated at B in Fig. 14, but without interfering with the proper operation, which is that the needle 27 in its inner position should not pass through the folded or doubled portion of the fabric 49. In its outer position, as stated, the needle clears not only the double portion of the fabric 49, but also the edge of the lace 28. This edge may be in the longitudinal plane D, or in any other longitudinal plane between C and E.

While I have shown my invention as applied to a two-needle sewing machine, with a folder and a pair of knives to co-operate with each of the needles, it will be obvious that many features of this invention may be utilized in connection with the machines having a single needle; thus, either the left-hand or the right-hand half of the mechanism illustrated, if used alone, would be fully operative to cut goods, fold the goods on one side of the cut, and sew a piece of lace or the like to the folded and

doubled portion. For this reason, in those claims which refer to only one needle, the terms "inside" and "outside," "inner" and "outer," "inward" and "outward," and the like, are used for the sake of convenience to distinguish one side from the other, but are not to be interpreted in a restrictive sense. In so far as the present application has features in common with my earlier application above referred to, as regards the arrangement of the folder, relatively to the cutting mechanism, such common features will be claimed in said earlier application. The present application also discloses certain novel features, invented by me but not claimed herein, in the construction and operation of the knives, and of the corresponding parts of the presser foot and of the throat plate, irrespective of their relation to the folder mechanism.

Certain claims of the present application which do not include cutting mechanism, will also fit the folder structure disclosed in my said earlier application, and to this extent my present application is a continuation of said earlier case.

I have described and illustrated a satisfactory and preferred embodiment of my invention, but it is obvious that changes may be made therein within the spirit and scope thereof as defined in the appended claims.

I claim

1. In a two-needle zig-zag sewing machine a presser foot having laterally elongated openings through which the needles are adapted to reciprocate, first at one end of such openings and then at the other, and provided with folders located close to said openings at the forward side thereof, said folders having operating ends which project downwardly from the presser foot and have outer faces oblique relatively to the line of feed, the oblique faces of the two folders converging forwardly, and the rear ends of said surfaces being substantially in longitudinal alignment with the

inner positions of the respective needles, and cutting devices located forwardly of said folders, and having their lines of action between the lines of action of the folders.

2. In a zig-zag sewing machine, a presser foot through which the needle is adapted to reciprocate first in an inner and then in an outer position, and provided with a folder located entirely forwardly of the transverse plane in which the needle operates, and closely adjacent to said plane, said folder having a straight operating end which projects downwardly in a curved relation from the presser foot and has an outer material engaging surface oblique relatively to the line of feed and adapted to fold the material from a flat horizontal position to a downwardly folded position, the obliquity of said surface being outward from front to rear, and the rear end of said surface being substantially in longitudinal alignment with the inner position of the needle, and a cutting device located forwardly of said folder, and having its line of action on the inside of the line of action of the folder.

3. In a sewing machine, a laterally-elastic folder comprising a material engaging portion arranged forwardly of the stitching point and a spring shank, and adjustment means engaging said spring shank for moving said folder in the direction opposite to the one in which the elasticity of the folder tends to move it, to adjust said folder to different operative positions.

4. In a sewing machine, a throat plate having a rearwardly-widening opening with an oblique edge, and a folder located above said opening and having an oblique portion depending into said opening adjacent to said edge and disposed entirely forwardly of the stitching point.

In testimony that I claim the foregoing as my invention, I have signed my name.

RALPH M. SHARAF.
